JAMES R. GILLETT, OF WESTFIELD, MASSACHUSETTS.

Letters Patent No. 77,477, dated May 5, 1868.

IMPROVEMENT IN WHIPS.

The Schedule referred to in these Letters Patent and making part of the same.

TO ALL WHOM IT MAY CONCERN:

Be it known that I, JAMES R. GILLETT, of Westfield, in the county of Hampden, and State of Massachusetts, have invented a new and useful Improvement in Whips; and I do hereby declare that the following is a full, clear, and exact description thereof, which will enable others skilled in the art to make and use the same, reference being had to the accompanying drawings, forming part of this specification.

Figure 1 represents a detail side view of my improved whip.

Figure 2 is a transverse section of the same.

Similar letters of reference indicate corresponding parts.

This invention relates to a new manner of protecting the core of whips from moisture, and from consequent injury, and consists in the application, around the core, and between the same and the outer covering, of a metallic lining, whereby the moisture will be completely excluded from the core, and whereby the whip will consequently be made sound and strong. Tin or other foil is the best material for that purpose. It is wrapped around the core, and then the covering is put on, the threads of which will be impressed in the surface of the foil, and will, consequently, hold the foil on the core, preventing it from shifting or otherwise becoming deranged on the core.

The metal will thus at all times retain its proper position around the core, and no water will be able to reach the latter.

By means of this metal lining the weight of the whip will be somewhat increased, and proportionately more at the thicker than at the thinner end; thereby the heft of the whip is more conveniently handled.

A, in the drawing, represents the core of a whip; B is the metallic lining, and C the outer covering of the same.

I claim as new, and desire to secure by Letters Patent—

Interposing a metallic lining, B, between the core A and covering C of a whip, substantially as and for the purpose herein shown and described.

JAMES R. GILLETT.
